UNITED STATES PATENT OFFICE

161,524

PAIR OF DUNGAREES

Alonzo Walter Patterson, Miami, Okla., assignor
to Patterson Manufacturing Company, Miami,
Okla., a corporation of Oklahoma

Application July 28, 1950, Serial No. 11,464

Term of patent 14 years

(Cl. D3—17)

To all whom it may concern:

Be it known that I, Alonzo Walter Patterson, a citizen of the United States, residing at Miami, in the county of Ottawa and State of Oklahoma, have invented a new, original, and ornamental Design for a Pair of Dungarees, of which the following is a specification, reference being had to the accompanying drawing, forming part hereof.

In the drawing:

Fig. 1 is a front view of a pair of dungarees showing my new design.

Fig. 2 is a rear view; and

Fig. 3 is an enlarged fragmentary view of the upper left side portion thereof.

I claim:

The ornamental design for a pair of dungarees, as shown.

ALONZO WALTER PATTERSON.
